TRANSPARENT GREENHOUSE

Philip B. Mims, Alexandria, Va.

Application March 11, 1958, Serial No. 49,991

Term of patent 14 years

(Cl. D13—1)

FIG. 1

FIG. 2

FIG. 3

Figure 1 is a perspective view of a transparent greenhouse showing my new design;

Figure 2 is a side elevational view thereof; and

Figure 3 is a fragmentary, vertical sectional view taken on the line 3—3 of Figure 2.

The design of the greenhouse disclosed is characterized by the front border having the configuration shown.

I. claim:

The ornamental design for a transparent greenhouse, as shown and described.
